FILING BOX

Harry H. Hughes, St. Louis, Mo.

Application August 2, 1940, Serial No. 349,536

12 Claims. (Cl. 229—23)

This invention relates to file boxes and it is an object of my invention to provide an inexpensive book-like file box for periodicals, maps, newspapers and the like, which may be shipped flat and subsequently easily assembled into a rigid file of attractive appearance.

In general, these objects are accomplished by providing a file box formed of moderately stiff cardboard consisting of two elements. The inner element is formed from a rectangular piece of cardboard into a rectangular box-like structure having open ends by creasing the cardboard parallel to its shortest dimension at suitable points and gluing the ends together. The outer element is formed of similar material and is creased to fold around the inner element. The ends of the outer element are provided with flaps adapted to be tucked into an open end of the inner element. The inner element does not have rigid reinforcements at the corners and may, therefore, be collapsed. After assembly, however, collapse of the inner element is prevented by the action of the flaps on the outer element. My file may, therefore, be shipped flat and easily assembled at its destination without the use of glue or special tools into a rigid file box.

Other objects will become apparent from the following detailed description and from the drawing, in which

Fig. 1 is an exploded view showing the general configuration and relationship of the component parts;

Fig. 2 is a perspective view of my assembled file box; and

Fig. 3 is a horizontal section taken along the line 3—3 of Fig. 2.

My file box consists of an inner element generally designated 11, and an outer element generally designated 12, which may be formed from a variety of semi-rigid materials such as solid kraft or ordinary cardboard, lined cardboard, cloth covered cardboard or covered corrugated paper board. The inner element 11 is formed from a rectangular blank of such material and comprises a flange section 13, a side 14, a top 15, a side 16, and a base 17. To construct this element, the blank which is originally flat, is creased along a line designated 18, parallel to an end 19 and spaced therefrom a distance approximately equal to one half of the desired width of the inner element. Another crease 21 is formed parallel to the first crease 18 and spaced therefrom a distance equal to the desired height of the inner element. A third crease 22 is formed parallel to the second crease 21 and

spaced therefrom a distance equal to the desired width of the inner element 11. A fourth crease 23 is formed parallel to crease 22, the distance between creases 22 and 23 being substantially equal to the distance between creases 18 and 21. The distance from crease 23 to end 24 is made substantially equal to the distance between creases 21 and 22.

The inner element 11 is assembled into its final form by folding the blank inwardly at each of the creases and fastening the flange section 13 to the base 17 by glue or other suitable means. As no reinforcement is used at the corners, the inner element may be folded into a flat section by moving the side 16 parallel to the side 14 until the two sides are in contact, thereby permitting shipment in a flat condition.

The outer element 12 is also formed from a substantially rectangular blank, the width of this blank being purposely made somewhat greater than the overall height of the inner element so that the assembled file will closely resemble a book. The width of the blank adjacent to each end, is reduced to define, in conjunction with creases 26 and 27, flaps 28 and 29, the width of the blank being made substantially equal to the distance between creases 18 and 21 on the inner element. The creases 26 and 27 are spaced inwardly from the respective ends of the blank, a distance slightly in excess of the width of the inner element and are parallel to the ends of the blank. Another crease 31 is formed parallel to crease 26 and spaced therefrom a distance equal to the depth of the inner element, defining a side 30. A crease 32 is formed similarly with respect to crease 27, defining another side 34 of the outer element. Creases 31 and 33 are spaced apart a distance substantially equal to the overall width of the inner element 11, and defines the back 36, which may be decorated or treated upon its external surface to closely resemble the back of a book.

The outer element 12 is preferably covered or printed with some design on its outer surface to present a pleasing appearance after assembly. The exterior portion of the back 36 may be printed, embossed, decorated by the silk screen process or provided with a suitable label to indicate the contents of the file, or an opening may be formed therein suitably positioned to reveal the title of the book or magazines within the file, the outline of such an opening being designated by the dotted line 35 in Fig. 1.

In shipment, the inner element may be collapsed in a manner previously described and the

outer element folded flat, thereby making a compact parcel for shipment. Upon arrival at its destination, the file may be easily assembled by placing the flap 28 in an open end of the inner element 11, folding the outer element 12 around the inner element 11 and finally inserting the other flap 29 in the same open end of the inner element as flap 28. As the flaps 28 and 29 are purposely formed with a width in excess of the width of the inner element, unintentional withdrawal of the flaps is prevented. These flaps, after being folded into the inner element, prevent collapse of the file and impart rigidity to the structure. It is to be noted from Fig. 3 that the flaps 28 and 29 are of sufficient length that, when they are brought together inside the inner element 11, an acute angle is formed between the flaps on the side facing the open end of the box. The flaps also hold the sides 32 and 34 of the outer element 12 snugly against the sides 14 and 16 of the inner element 11, providing in effect a double wall section which greatly increases the strength and durability of my file.

Due partially to the inherent resiliency of the materials used to form the outer element 12, and partially to the width of the sides of the inner element 11, the flaps 28 and 29 will tend to spring inwardly towards each other within the inner element, except, of course, when the file is completely filled. As shown in Fig. 3, this action of the flaps tends to hold the contents of a partially filled file in a vertical position and also tends to hold the contents in place when the file is accidentally tilted.

Certain of the details mentioned in the foregoing description may be modified. For example, it is not essential that the outer element 12 have a height greater than that of the inner element, although it is believed that this contributes to the appearance of my file. Likewise, the flaps on the end of the outer element 12 are not necessarily integral therewith, but may be attached by tape or other suitable means.

The utility of my file appears to be obvious from the foregoing description. Magazines, books, maps, papers, bulletins, recipes, pictures, correspondence, and the like, which would ordinarily be piled on library shelves in horizontal position may be placed in my file and be retained in vertical position, thereby greatly increasing the accessibility of the material, economizing on storage space and improving the appearance. It is also apparent that my file is not only economical to manufacture, but also is easily assembled by unskilled purchasers and users, without the use of glue or other fastening means. Economy of materials is effected by the use of rectangular blanks, which may be cut and formed without waste.

The foregoing detailed description has been made in compliance with section 4888 of the Revised Statutes, but I do not wish to be specifically limited to all of the details herein set forth, as obviously certain modifications may be made therein without departing from the true spirit and scope of my invention as defined in the appended claims.

I claim:

1. A file box comprising a box-like inner element having open ends, the depth of said element being greater than its width, a separate outer element adapted to fold around the inner element and close one open end, and flaps on the extremities of the outer element, each of said flaps having a width greater than the width

of the inner element, said flaps folding into the open end of the inner element and cooperating with the inner element to retain the two elements in rigid relation.

5. A file box including a rectangular box-like inner element being open at least at one end, the depth of the element being greater than its width, an outer element adapted to partially enclose the inner element, the unfolded length of 10 the outer element being greater than the sum of twice the depth plus three times the width of the inner element, and flaps integral with the ends of the outer element adapted to extend into the open end of the inner element leaving the one 15 end of said element open.

3. A file box including a rectangular inner element having open ends, a separate outer element partially enclosing the inner element, and means integral with the outer element cooperating with 20 the inner element for maintaining the elements in assembled relation, said means including flaps formed on each end of the outer element adapted to be folded into an open end of the inner element, the width of the flaps being greater than the width of the open end of the inner element but less than the depth of said element whereby 25 accidental withdrawal of the flaps is prevented.

4. A file box for filing a plurality of loose pamphlets and the like, consisting of only two 30 box-forming elements, one an inner element of rectangular cross section having open ends, and the other an outer element folding around the inner element, covering one open end of the inner element, and having flaps folding into the uncovered end of the inner element; said flaps being wide enough, each wider than half the 35 width of the opening, so that under influence of their resilient tendency to unfold they will strike one another and prevent the box from accidentally coming apart and, if a thin pamphlet 40 or the like is in the box, will strike opposite sides thereof and hold it upright; the depth of the box being sufficient to receive the flaps each lying flat against the wall of the inner element around 45 which it is folded.

5. A file box comprising an inner box-like element of rectangular cross-section having open ends, the depth of the inner element being in excess of its width, and a separate outer element 50 folding around the inner element and closing one of the said open ends, said outer element having a flap on each of the opposite ends thereof folding into the uncovered end of the inner element, each of the flaps being wider than the open 55 end of the inner element and cooperating with the inner element to retain the elements in rigid relation.

6. A file box comprising an inner box-like element of rectangular cross-section having open 60 ends, an outer element folding around the inner element so as to cover one of the open ends of the inner element, said outer element having a flap on each of the opposite ends thereof folding into the uncovered end of the inner element, each of the flaps being wider than one-half the width of the open end of the inner element so that the two flaps coact to retain each other within the inner element, thereby retaining the inner and outer elements in rigid relation.

7. A file box comprising an inner box-like element of rectangular cross-section having open ends, and an outer element folding around the inner element so as to cover one of the open ends of the inner element, said outer element having 70 a flap on each of the opposite ends thereof fold-

ing into the uncovered end of the inner element, the two flaps being of sufficient width to contact each other before they enter the plane of the open end of the inner element so as to retain each other within the inner element, thereby retaining the inner and outer elements in rigid relation.

8. A file box comprising an inner element of rectangular cross-section having open ends, an outer element folding around the inner element and covering one open end of the inner element, said outer element having a flap on each of the opposite ends thereof folding into the uncovered end of the inner element, said flaps each being wider than one-half the width of the open end of the inner element and of sufficient width to contact with the other while the angle formed between their faces facing the open end of the inner element is an acute angle so as to retain each other within the inner element.

9. A file box of board-like material comprising a box-like element of rectangular cross section having spaced parallel side walls connected substantially at their top and bottom edges by spaced top and bottom walls, the front and back being open substantially throughout, the depth of the side walls, measured from the front to the back of the element, being in excess of the distance between the side walls, an outer element connected to one side of the box-like element and including a back portion extending across the back of said box-like element and having integral therewith a side portion extending along the opposite side wall of the box-like element from the back to the front of the box-like element, and an integral flap on the free end of said side portion projecting beyond the side portion a distance greater than the distance between the side walls but less than the depth of the side wall and adapted to fold into the open front of the box-like element to form a sturdy box.

10. A file box of board-like material comprising a collapsible box-like element of rectangular cross section having spaced parallel side walls connected substantially at their top and bottom edges by spaced top and bottom walls along fold lines, the front and back being open substantially throughout, the depth of the side walls measured from the front to the back of the element being in excess of the distance between the side walls, an outer element connected to one side of the box-like element and including a back portion extending across the back of said box-like element and having integral therewith a side portion extending along the opposite side wall of the box-like element from the back to the front of the box-like element, and an integral flap on the free end of said side portion projecting beyond the side portion a distance greater than the dis-

tance between the side walls but less than the depth of the side wall and adapted to fold into the open front of the box-like element to form a sturdy box.

5 11. A file box for receiving magazines or the like made of semi-rigid or rigid board-like material comprising a box-like element of rectangular cross section having spaced parallel side walls connected substantially at the top and bottom edges by spaced top and bottom walls and collapsible to a flat form along fold lines, at least the front of the box-like element being open, the depth of the side walls measured from the front to the back of the element being in excess of the distance between the side walls, an outer element also collapsible to flat form along fold lines connected to one side of the box-like element and having a back portion adapted to extend across the back of said box-like element and having integral therewith a side portion extending along the outside of the opposite side wall of the box-like element from the back to the front of the box-like element, and a flap on the free end of said side portion adapted to fold into the open front of the box-like element, and engaging the box-like element in such a manner as to maintain the two elements in rigid relationship while the open side of the box-like element is maintained open and accessible for the passage therethrough of magazines and the like into and out of the box-like element.

10 12. A book-shaped file box of board-like material comprising a collapsible box-like element of rectangular cross section having spaced parallel side walls connected substantially at the top and bottom edges by spaced top and bottom walls along fold lines, the front and back being open substantially throughout, the depth of the side walls measured from the front to the back of the element being in excess of the distance between the side walls, and an outer element including a pair of side portions and a back portion, the side portions being coextensive with the depth of the collapsible box-like element, the back portion being substantially coextensive with the open back of the collapsible box-like element, the outer element being adapted to fold around the collapsible box-like element substantially closing the open back of said element, and a flap on the front edge of each side of the outer element adapted to fold into the open front of the collapsible box-like element and to engage the box-like element in such a manner as to maintain the two elements in rigid relationship while the open side of the box-like element is maintained open and accessible for the passage therethrough of pamphlets and the like into and out of the box-like element.

HARRY H. HUGHES.
